US00D931311S

(12) **United States Design Patent** (10) Patent No.: US D931,311 S
Casse et al. (45) Date of Patent: ** Sep. 21, 2021

**(54) DISPLAY SCREEN OR PORTION THEREOF
WITH GRAPHICAL USER INTERFACE**

(71) Applicant: **Fisher & Paykel Healthcare Limited**,
Auckland (NZ)

(72) Inventors: **Benjamin Wilson Casse**, Auckland (NZ); **Christopher Harding Campbell**, Auckland (NZ); **Katarzyna Sobolewska**, Auckland (NZ); **David Robert Keith Walker**, Auckland (NZ)

(73) Assignee: **Fisher & Paykel Healthcare Limited,**
Auckland (NZ)

(**) Term: 15 Years

(21) Appl. No.: 29/678,687

(22) Filed: **Jan. 30, 2019**

CLAIM

The ornamental design for a display screen or portion thereof with graphical user interface, as shown and described.

DESCRIPTION

FIG. 1 is a front view of a display screen or portion thereof with a graphical user interface showing our new design; and, FIG. 2 is a front view of a display screen or portion thereof with a graphical user interface in accordance with a second embodiment.

The broken lines, including those showing a display screen or portion thereof and those depicting portions of a graphical user interface, form no part of the claimed design.

1 Claim, 2 Drawing Sheets
